UNITED STATES PATENT OFFICE.

CHARLES L. MOORE AND CORTEZ V. PUGH, OF BOWLING GREEN,
MISSOURI.

BURIAL APPARATUS.

SPECIFICATION forming part of Letters Patent No. 605,555, dated June 14, 1898.

Application filed May 18, 1897. Serial No. 637,065. (No model.)

To all whom it may concern:

Be it known that we, CHARLES L. MOORE and CORTEZ V. PUGH, citizens of the United States, residing at Bowling Green, in the county of Pike and State of Missouri, have invented a new and useful Burial Apparatus, of which the following is a specification.

This invention relates to mechanical appliances to facilitate the lowering of a coffin or casket into a grave and which will receive the coffin at one end of the grave thereby obviating the inconvenience, annoyance, and danger attendant upon placing the coffin upon apparatus located directly over the grave. The appliance bearing the load is moved upon a track from the end of the grave to a position directly thereover, and the coffin is lowered at a regulated speed.

The object of the invention is the provision of an apparatus for the purpose aforesaid which will be light, neat, comprise a few operating parts easily handled, and which is open, so that access can be had to and every part be at all times under observation.

Other objects and advantages are contemplated and will become apparent as the nature of the invention is understood; and to this end the improvement consists of the novel features and details of construction, which hereinafter will be more fully illustrated, described, and claimed.

In the accompanying drawings is illustrated an embodiment of the invention, although slight changes in the details and arrangement may be made without departing from the spirit of the invention.

In said drawings, Figure 1 represents the apparatus in position to receive the coffin. Fig. 2 is a view similar to Fig. 1 on a larger scale, showing the relative position of the apparatus after the coffin has been placed thereon and the said apparatus moved to a position directly above the grave, the outer end portion of the track being broken away. Fig. 3 is a view similar to Fig. 2, showing the coffin partially lowered. Fig. 4 is a perspective view of the apparatus viewed from a different point. Fig. 5 is a detail view of the actuating mechanism. Fig. 6 is a top plan view of the actuating mechanism, the dotted lines showing the crank and pinion thrown

out of gear. Fig. 7 is a view of the actuating mechanism from the inner side, showing it in operative relation. Fig. 8 is a detailed view to show more clearly the end braces. 55

Referring to the drawings, in which similar numerals denote corresponding parts in all the figures, 1 indicates the frame of the apparatus, and is substantially rectangular in shape, and is composed of tubular side and end bars, which are jointed at their angles by means of L-couplings, such as are commonly employed for connecting water and gas pipes where they extend relatively at right angles. This frame is mounted upon 60 grooved wheels 2, which are journaled in the lower ends of inverted-U-shaped hangers 3, the latter straddling the side bars 4 of the frame and attached thereto by bolts 5. There will be four supporting-wheels 2, and they 65 will be located near the four corners of the frame, one near each end of the side bars. Longitudinal shafts 6 extend parallel with the side bars 4 and are journaled in the upper ends of a series of knees 7, which are mounted 70 upon the side bars 4 and are held thereon in the adjusted position by means of binding-screws 8. By loosening the binding-screws 8 the knees 7 can be adjusted so as to bring the longitudinal shafts 6 in closer relation or 75 move them farther apart, as desired. Sprocket-pinions 9 are mounted upon the adjacent ends of the shafts 6 and are of like size, so as to secure a uniform movement of the said shafts when the apparatus is in operation. 85

The actuating mechanism for the longitudinal shafts is located at one end of the frame and is mounted upon a sleeve 10, secured upon the end bar 11 in any desired manner, preferably by means of a binding-screw 12. 90 Parallel wings 13 extend vertically from the sleeve 10, and a shaft 14 is journaled in one end of the said wings and is provided at its outer end with a gear-wheel 15 and at its inner end with a pinion 16, and this gear-wheel 95 is provided on the inner side with a peripherally-grooved ring 17, which receives a strap 18, by means of which the descent of the coffin is controlled in the manner presently to be explained. One end of the strap 18 is secured to the sleeve 10, and after passing nearly around the ring 17 the said strap has 100

its opposite end attached to a lever 19, which has pivotal connection at its lower end with the end bar 11, and by pressing outwardly and downwardly upon the lever 19 the said strap 18 will be caused to grip the ring 17 more or less tightly and control the lowering of the coffin, as will be readily understood. A hub portion 20 is formed on the inner side of the pinion 16 and has spurs 21 projecting outwardly therefrom, which are engaged by the bent end of a pivoted pawl 22, so as to lock the mechanism in the required position. The pawl 22 is pivoted to a side of one of the wings 13 and is operated by hand when it is required to release or hold the actuating mechanism in check. A pinion 23, similar to the pinion 16, is in mesh with the latter and is mounted upon a journal 24, extending parallel with the shaft 14, and a sprocket-pinion 25 is formed on the outer side of the pinion 23 or is caused to revolve therewith in any manner, so that the pinion 23 and the sprocket 25 will revolve together as a unitary part. A sprocket-pinion 26 of corresponding size to the sprocket-pinion 25 is formed on or secured to the outer side of the pinion 16 and revolves therewith, and the sprocket-pinions 25 and 26 have a like number of teeth, so as to impart a similar movement to the longitudinal shafts 6. Sprocket-chains 27 and 28 connect the respective sprocket-pinions 25 and 26 with the respective sprocket-pinions 9 on the ends of the shafts 6. A shaft 29 is mounted in the opposite end of the wings 13 to that carrying the shaft 14 in such a manner as to have a limited longitudinal movement and is provided at its outer end with a crank 30 and a pinion 31, the latter meshing with the gear-wheel 15, so as to rotate the latter when it is required to impart a positive movement to the longitudinal shafts 6 for the purpose of winding the tapes or straps 32 upon the spools 33, mounted upon the said longitudinal shafts. This shaft 29 is capable of longitudinal movement to admit of the pinion 31 being moved into or out of gear with the gear-wheel 15, according as it is required to connect the shafts 6 with or disconnect them from the actuating mechanism. The spools 33 are mounted upon the shafts 6 and are capable of adjustment thereon to admit of their separating or coming closer together, according to the length of the coffin to be lowered into the grave, and these spools are prevented from turning independently on the shafts by a feather-and-spline connection, the longitudinal rib 34 entering a corresponding groove or notch in the bore of the spool co-operating therewith. The straps or tapes 32 have their end portions wound in reverse directions upon corresponding spools 33, so that the said ends will be paid out or unwound from the spools at the same rate of speed, thereby lowering the coffin and maintaining it in a horizontal position.

The portable track 35 is composed of two sections 36 and 37, which are removably con-

nected together, so as to admit of the length of the track being reduced to a proper size for convenient handling when required for use. Each section of the track is composed of longitudinal sills surmounted by rails upon which the grooved wheels 2 travel and which guide the apparatus in its movements. One of the sections is located immediately above and encircles the newly-made grave, and the opposite section forms a continuation thereof and projects at one end of the grave a sufficient distance to receive and support the apparatus, as shown most clearly in Fig. 1. If desired, one or both sections of the track can be suitably propped to bring the parts into an approximately horizontal position. Obviously where the ground is perfectly level the track will be placed thereupon without requiring any propping; but where the ground is hilly or uneven a propping and bracing of the track will be necessary to the successful operation of the appliance.

After a grave has been prepared the track is adjusted about in the position shown in Figs. 1, 2, and 3, and the apparatus is placed upon that portion of the track located at one end of the grave, care being taken to have the end portions of the straps or tapes wound upon the corresponding and co-operating spools, so that the middle portion of said straps or tapes will be taut and occupy a horizontal plane. The pawl 22 is brought into engagement with one of the spurs 21, so as to lock the actuating mechanism and hold the straps in position to receive and support the coffin, which latter is placed in position upon the straps by the pall-bearers walking upon either side of the outer end portion of the track. After the coffin has been deposited upon the apparatus the latter is moved upon the track to a position directly above the grave, and when it is required to lower the coffin the pawl 22 is disengaged from the spurs 21 and the crank is moved outward, so as to disengage the pinion 31 from the gear-wheel 15, and the lever 19 is manipulated to permit the weight of the coffin and contents to draw the straps 32 from the spools 33, when the said coffin will descend into the grave, the rapidity of the descent being controlled by pressing upon the lever 19, so as to cause the strap 18 to bind upon or grip the ring 17 more or less tightly. After the coffin has reached the bottom of the grave the straps 32 are disengaged therefrom in the usual manner, either by disconnecting one end from one of the spools 33 and drawing upon the opposite end of the strap or by loosening the straps and slipping them from beneath the ends of the coffin, as commonly practiced. After the straps have been disengaged from the coffin in either of the ways mentioned or in any other desired and convenient manner the end portions of the said straps are wound upon their respective spools by bringing the pinion 31 into mesh with the gear-wheel 15 and by rotating the crank 30, as will be readily understood.

The longitudinal shafts 6 are braced by end stays 39, similar in general outline to the knees 7 and which are attached at their lower ends to the end frame-bar opposite to the actuating mechanism. Caps 38 are fitted to the ends of the shafts 6 opposite to the sprocket-pinions 9 and coöperate with the latter to prevent longitudinal movement of the shafts in their bearings. Oppositely-extending braces 40 connect the longitudinal shafts with the sleeve 10 and serve to hold the shafts in fixed relation after the parts have been properly adjusted. These braces are composed of parts which are adjustably connected together to admit of the relative adjustment of the longitudinal shafts when it is required to secure the proper tension upon the sprocket-chains 27 and 28. It will be understood that the braces 39 are connected with the frame and the longitudinal shafts in such a manner as to admit of the adjustment of the longitudinal shafts in the manner set forth.

The present invention obviates the necessity of the pall-bearers walking along the edges of the grave and facilitates the placing of the coffin upon the lowering apparatus and makes provision for the proper deposition of the coffin without necessitating the obstructing of the grave and the burial proceedings, as is generally the case where the services of the ordinary laborer are required for lowering the coffin into the grave. The apparatus is light and portable, and when it is required to attain the proper tension upon the sprocket-chains the knees 7 can be loosened and moved upon the side bars 4, so as to attain the desired end, the binding-screws 8 allowing for the loosening of the knees and for the tightening of the same after being properly adjusted.

It will be understood that the track may be provided in as many sections as required, and in the event of the ground being uneven the spaces or depressions between elevated points will be provided with blocks or a suitable trestle-work for supporting the track extending thereover. The wheels or rolling supports 2 may be in the form of ordinary casters, so that they may turn to adapt themselves to any curvature in the track, thereby obviating binding.

Various changes in the form, proportion, and the minor details of construction may be resorted to without departing from the principle or sacrificing any of the advantages of this invention.

Having thus described the invention, what is claimed as new is—

1. In a burial apparatus, the combination of a frame comprising longitudinal bars to come upon opposite sides of the grave, knees having bearings at both ends and mounted at their inner ends upon the said longitudinal bars to slide and turn thereon to secure any longitudinal adjustment and to spread their free ends more or less, means for securing the knees in an adjusted position upon

the frame-bars, longitudinal shafts parallel with each other and with the side frame-bars, mounted in the bearings at the free or outer ends of the knees, and actuating mechanism applied to the frame for simultaneously turning the shafts at equal speed, substantially in the manner set forth.

2. In a burial apparatus, the combination of a rectangular frame, knees mounted to turn and slide upon side bars of the frame, means for securing the knees in an adjusted position, parallel shafts mounted in bearings at the free ends of the knees, spools adjustable on said shafts and caused to revolve therewith at any adjusted position by a feather - and - spline connection, actuating mechanism for positively rotating the shafts in reverse directions at an equal rate of speed, a detent and a brake device applied to the actuating mechanism, and straps or tapes having their end portions secured to and wound in reverse directions upon corresponding or transversely-alining spools, substantially as set forth for the purpose described.

3. In a burial apparatus, the combination of longitudinally-disposed shafts, straps or tapes having their end portions reversely wound upon the said shafts, intermeshing pinions having sprocket-pinions revolving therewith, sprocket-chains for connecting the sprocket-pinions with corresponding sprocket-pinions on the ends of the longitudinal shafts, a detent mechanism applied to one of the pinions for holding the mechanism in check, and actuating mechanism for positively operating the said pinions, substantially as and for the purpose set forth.

4. In a burial apparatus, the combination of a frame, longitudinal shafts journaled upon the frame, straps or tapes having their end portions reversely wound upon the shafts, a sleeve secured upon a frame-bar and having extensions, a shaft journaled in the extensions and provided with a gear-wheel and a pinion, the latter having a hub portion formed with spurs, a pawl for engaging with the spurs, a ring on the side of the gear-wheel, a strap engaging with the ring, a lever having the strap connected therewith, a second pinion meshing with the first-mentioned pinion, sprocket-pinions revolving with the aforesaid pinions and connected by means of sprocket-chains with sprocket-pinions on the said longitudinal shafts, and a crank having a pinion operatively connected therewith and adapted to be thrown in and out of mesh with the said gear-wheel, substantially as set forth for the purpose described.

In testimony that we claim the foregoing as our own we have hereto affixed our signatures in the presence of two witnesses.

CHARLES L. MOORE.
